[57] CLAIM

We claim the ornamental design for an over-the-door multiple hook, as shown and described.

DESCRIPTION

FIG. 1 is a top, left front perspective view of an over-the-door multiple hook showing a first embodiment of our new design.

FIG. 2 is a left side elevational view thereof.

FIG. 3 is a right side elevational view thereof.

FIG. 4 is a top plan view thereof.

FIG. 5 is a bottom plan view thereof.

FIG. 6 is a front elevational view thereof.

FIG. 7 is a rear elevational view thereof.

FIG. 8 is a top, left front perspective view of an over-the-door multiple hook showing a second embodiment of our new design.

FIG. 9 is a left side elevational view thereof.

FIG. 10 is a right side elevational view thereof.

FIG. 11 is a top plan view thereof.

FIG. 12 is a bottom plan view thereof.

FIG. 13 is a front elevational view thereof; and,

FIG. 14 is a rear elevational view thereof.
